UNITED STATES PATENT OFFICE.

TIMOTHY STEBBINS, OF DAVENPORT, IOWA, ASSIGNOR TO RED JACKET MANUFACTURING COMPANY, OF DAVENPORT, IOWA, A CORPORATION OF IOWA.

PUMP.

SPECIFICATION forming part of Letters Patent No. 763,935, dated June 28, 1904.

Application filed August 4, 1902. Serial No. 118,285. (No model.)

To all whom it may concern:

Be it known that I, TIMOTHY STEBBINS, a citizen of the United States, and a resident of Davenport, in the county of Scott and State 5 of Iowa, have invented certain new and useful Improvements in Pumps, of which the following is a full, clear, and exact description.

The object of my invention is to provide a 10 simple, cheap, and economical single-acting pump which is so constructed that the plunger, the puppet-valve, and the well-pipe above the lower cylinder can be easily removed whenever occasion requires it and easily and accurately 15 replaced and secured in place without encountering the difficulties heretofore besetting such operation. This I accomplish by the means hereinafter described and as particularly pointed out in the claims.

20 In the drawings, Figure 1 is a side elevation of my improved pump. Fig. 2 is a side elevation of the portion thereof adjacent to and including the platform or base-plate broken away from the rest of the pump and illustrating 25 the well-pipe disengaged from said base-plate. Fig. 3 is a similar view showing said base-plate and the parts coöperating therewith which are attached to the well-pipe in section. Fig. 4 is a side elevation of the portion 30 of the pump adjacent to and including the lower cylinder broken away from the remainder of the pump. Fig. 5 is a cross-section taken on dotted line 5-5, Fig. 2, looking in the direction indicated by the arrows.

35 In the drawings, A represents the super-structure of a pump or the portion thereof above the surface. The lower portion of this pump-frame A consists of a continuation of the well-pipe B, such as commonly used in 40 single-acting pumps, and extends from the pump-head to the lower cylinder C.

The hole in the platform D down through which the well-pipe B extends is surrounded by a concentric base-plate E, which supports 45 the lower cylinder by means of two or more rods *aa*, the upper ends of which are suitably secured to the flange of said base-plate and the lower ends thereof in lugs projecting from the upper end of the lower cylinder,

substantially as shown in the drawings. The 50 lower end of the well-pipe is provided with a suitable nut *b*, which has a circumferential flange *c* projecting from its lower portion, whose lower edge is rabbeted and has a rubber gasket *d* seated against the shoulder thus 55 made. The relative diameters of the said nut *b* and the upper end of the lower cylinder are such that when the well-pipe is moved downward until the shoulders of the rabbeted flange of nut *b* are seated in the upper chamfered edges of the mouth at the upper end of said cylinder it will close the same. In order to make this joint water-tight, I have used the gasket *d*, and in order to compress said gasket in its seat and make it a thorough packing 60 65 I provide the well-pipe at a point just below the base-plate with a suitable collar F, and I surround the well-pipe above this collar with an exteriorly-screw-threaded compression-sleeve G, which is tapped into the central 70 opening of and carries with it the flanged cover or closure-plate H. This closure-plate is preferably of a bell shape, and near the annular edges of its mouth it is provided with a circumferential flange *c*, which is provided with 75 three recesses *f* and preferably midway between these recesses is provided with stop-lugs *g*.

The base-plate has projecting upward from the margins of its central opening three suitably-reinforced inverted-L-shaped lugs *h* *h*, and when it is desired to close the upper end of the lower cylinder of the pump, as herein-before set forth, the closure-plate is so positioned that when it is seated the L-shaped lugs 80 *h* will pass up through the recesses of the flange of the same, which latter thus gets below the overhanging arms of said lugs *h*, so that by turning the closure-plate said flange is moved under and confined against vertical 85 displacement by said lugs. By screwing the sleeve G downward until its lower edges bear against the collar F it forces the well-pipe downward, and thus compresses the packing and makes a secure water-tight joint between 90 the nut or the lower end thereof and the upper end of the cylinder.

The puppet-valve K, which is shown in Fig.

3 as lifted out of the cylinder, has a vertical independent play in a suitable seat in the lower end of the cylinder. It is often desirable to remove the puppet-valve, however, and this 5 is done in a well-known way by means of an interiorly-screw-threaded boss *k*, suspended from and supported by the plunger *I*, fast on the end of the plunger-rod *J*. This plunger reciprocates in the lower cylinder and is 10 greater in diameter than the well-pipe above it. Consequently when it is desired to move the puppet-valve the upper end of the plunger-rod is disconnected from the handle, and by turning it the boss *k* is screwed down over 15 the screw-threaded stud *h* of the puppet-valve, whereupon said puppet-valve, plunger, plunger-rod, and well-pipe after the cover or closure-plate has been disengaged from the base-plate are lifted bodily together out of the 20 well and off of the lower cylinder. When it is desired to replace the upper portion of the well-pipe and the pump-head, the well-pipe after the packing-nut has been satisfactorily adjusted is lowered down through the base-plate until said packing-nut rests in its seat 25 in the upper edges of the lower cylinder, whereupon the closure-plate or cover is manipulated so as to close the central opening of the base-plate, and thus center the well-pipe 30 and the pump, and the gland nut or sleeve turned so as to bear down upon the collar *F* and press the packing-nut tightly down in its seat to such an extent that the gasket *d* makes the joint between the nut and the cylinder 35 perfectly water-tight.

While it is not deemed absolutely necessary, yet it is advisable to prevent the well-pipe from turning when the gland-nut is being manipulated, which when the parts become 40 rusted it is liable to do. This I accomplish by means of a bifurcated lug *m*, depending down from the cover, and by providing the collar *F* with a laterally-projecting stud or lug *n*, which when cover is put in place to 45 close the central opening of the base-plate is straddled by said lug *m*, and thus prevents the independent rotative movement of the well-pipe, while at the same time permitting of the vertical movement of the cover and 50 well-pipe to accomplish the objects of the invention, as hereinbefore set forth.

What I claim as new is—

1. In a pump, the combination with the lower cylinder, and base-plate from which said cylinder is suspended, and which has an enlarged central opening therein and retaining-lugs arising therefrom, of a superimposed well-pipe alining with said cylinder which extends through said base-plate and has an enlargement just below the same, a flanged cover adapted to interlock with said base-plate, and an exteriorly-threaded sleeve which is tapped into the central opening of and supports said cover.

65 2. In a pump, the combination with the

lower cylinder, a base-plate having an enlarged central opening therein and retaining-lugs arising therefrom, means for suspending said cylinder below said base-plate, a superimposed well-pipe alining with said cylinder which extends through said base-plate and has an enlargement just below the same, a flanged cover adapted to interlock with said base-plate, and an exteriorly-threaded sleeve which is tapped into the central opening of and supports said cover.

3. In a pump, the combination with the lower cylinder, and base-plate from which said cylinder is suspended, and which has an enlarged central opening and retaining-lugs arising therefrom, means for suspending said cylinder below said base-plate, of a superimposed well-pipe alining with said cylinder which extends through said base-plate and has an enlargement just below the same, a packing-nut 85 on the lower screw-threaded end of said pipe, a flanged cover having recesses in its outer edges which interlock with said base-plate and an exteriorly-threaded sleeve which is tapped into the central opening of and supports said 90 cover.

4. In a pump, the combination with the lower cylinder, and base-plate from which said cylinder is suspended and which has an enlarged central opening, means for suspending 95 said cylinder below said base-plate, of a superimposed well-pipe alining with said cylinder extending down through said base-plate, and vertically removable therethrough, and means engaging said base-plate for effecting an operative closure between the lower end of said well-pipe and said cylinder.

5. In a pump, the combination with the lower cylinder, and base-plate from which said cylinder is suspended and which has an enlarged central opening, means for suspending said cylinder below said base-plate, of a superimposed well-pipe alining with said cylinder extending down through said base-plate, and vertically removable therethrough, and adjustable means engaging said base-plate for effecting an operative closure between the lower end of said well-pipe and said cylinder.

6. In a pump, the combination with the lower cylinder, and base-plate from which said cylinder is suspended and which has an enlarged central opening, means for suspending said cylinder below said base-plate, of a superimposed well-pipe alining with said cylinder extending down through said base-plate, and vertically removable therethrough, a packing-nut on the lower screw-threaded end of the same, and means engaging said base-plate for effecting an operative closure between the lower end of said well-pipe and said cylinder.

7. In a pump, the combination with the lower cylinder, and base-plate from which said cylinder is suspended and which has an enlarged central opening, means for suspending said cylinder below said base-plate, of a super-

imposed well-pipe alining with said cylinder extending down through said base-plate, and vertically removable therethrough, a packing-nut on the lower screw-threaded end of the same, and adjustable means engaging said base-plate for effecting an operative closure between the lower end of said well-pipe and said cylinder.

8. In a pump, the combination with the lower cylinder, and base-plate from which said cylinder is suspended, and which has an enlarged central opening therein and has inverted-L-shaped retaining-lugs arising from the margins of said opening, of a superimposed well-pipe alining with said cylinder which extends through said base-plate and has an enlargement just below the same, a flanged cover having recesses in its outer edges, and an exteriorly-threaded sleeve which is tapped into the central opening of and supports said cover.

9. In a pump, the combination with the lower cylinder, and base-plate from which said cylinder is suspended, and which has an enlarged central opening therein and has inverted-L-shaped retaining-lugs arising from the margins of said opening, of a superimposed well-pipe alining with said cylinder which extends through said base-plate and has an enlargement just below the same, a packing-nut on the lower screw-threaded end of said pipe, a flanged cover having recesses in its outer edges, and an exteriorly-threaded sleeve which is tapped into the central opening of and supports said cover.

10. In a pump, the combination with the lower cylinder, and base-plate from which said cylinder is suspended, and which has an enlarged central opening therein and has inverted-L-shaped lugs arising from the margins of said opening, of a superimposed well-pipe alining with said cylinder which extends through said base-plate, a collar, a flanged cover having recesses in its outer edges movable longitudinally independent of said collar, but preventing the independent rotative motion thereof, and an exteriorly-threaded sleeve tapped into the central opening of and supporting said cover.

11. In a pump, the combination with the lower cylinder, and base-plate from which said cylinder is suspended, and which has an enlarged central opening therein and has inverted-L-shaped retaining-lugs arising from the margins of said opening, of a superimposed well-pipe alining with said cylinder which extends through said base-plate, a packing-nut on the lower screw-threaded end of said pipe, a collar, a flanged cover having recesses in its outer edges movable longitudinally independent of said collar, but preventing the independent rotative motion thereof and an exteriorly-threaded sleeve tapped into the central opening of and supporting said cover.

12. In a pump, the combination with the lower cylinder, and base-plate from which said cylinder is suspended, and which has an enlarged central opening therein and has inverted-L-shaped retaining-lugs arising from the margins of said opening, of a superimposed well-pipe alining with said cylinder which extends through said base-plate, a collar thereon having a laterally-extending lug, a flanged cover having recesses in its outer edges, and having a bifurcated lug depending therefrom that engages said collar-lug, and an exteriorly-threaded sleeve tapped into the central opening of and supporting said cover.

13. In a pump, the combination with the lower cylinder, and base-plate from which said cylinder is suspended, and which has an enlarged central opening therein and has inverted-L-shaped retaining-lugs arising from the margins of said opening, of a superimposed well-pipe alining with said cylinder which extends through said base-plate, a packing-nut on the lower screw-threaded end of said pipe, a collar thereon having a laterally-extending lug, a flanged cover having recesses in its outer edges, and having a bifurcated lug depending therefrom that engages said collar-lug, and an exteriorly-threaded sleeve tapped into the central opening of and supporting said cover.
